POWER MECHANISM FOR TYPEWRITING MACHINES

James F. Smathers, Rochester, N. Y., assigner to International Business Machines Corporation, New York, N. Y., a corporation of New York

Application February 6, 1947, Serial No. 726,924

6 Claims. (Cl. 197—17)

1

This invention relates to typewriting machines and more particularly typewriters in which the various mechanisms are operated by power.

The primary object of the present invention is to provide an improved power operating mechanism for typewriters.

An object is to provide an improved power mechanism of the type in which the typewriter mechanisms and instrumentalities are selectively coupled to a main power actuator by coupling devices selectively controlled by the keys of the typewriter.

An object is to provide a power mechanism which is more positive in its action.

Another object is to provide a power mechanism in which the possibility of a misoperation is reduced to a minimum.

An object is to provide a novel means for coupling the instrumentalities of the typewriter, such as the type bars, to the main power actuator.

An object is to provide a power mechanism in which the power actuator remains inactive until the coupling device is positively coupled to the main actuator.

Other objects of the invention will be pointed out in the following description and claims and illustrated in the accompanying drawings, which disclose, by way of example, the principle of the invention and the best mode, which has been contemplated, of applying that principle.

In the drawing:

The drawing shows a vertical section of a power mechanism embodying the present invention.

The numeral 10 designates a type bar which is pivotally mounted at 11 to swing in an arc of approximately 90° to effect an impression on the work sheet on the usual platen 12. It will be understood that there is a plurality of the type bars 10 and each may be provided with two or more type characters 10a, the selection of which, in the present case, may be effected by shifting the platen 12 in a well known way. The present invention relates to the means for operating the type bars 10 to effect printing operations and accordingly the shift mechanism by means of which the characters 10a of a type bar 10 are selected will not be disclosed.

Associated with each type bar 10 is a key 13 pivoted on a cross rod 14, the key being guided by a suitable comb 15 and restored by a spring 16. All of the type bars in the machine are operated by power mechanism which includes a single cam unit 17 of conventional form pivoted at 18 to a fixed part of the machine and cooperating

with the power roller 19 which rotates in the direction of the arrow.

The cam unit 17 is connected by a link 20a to a bell crank 20 pivoted at 21 to a fixed part of the machine. The bell crank 20 is connected by a link 22 to one arm 23a of an operating bail 23. When the key 13 is depressed, the cam unit 17 is rendered operative by the power roller 19, through means described later herein, thereby causing the cam unit 17 to be rocked in a clockwise direction, drawing down the link 20a, and rocking the bell crank 20 clockwise. This bell crank, through the link 22, rocks the arm 23a in a clockwise direction and causes the bail 23 to travel upwardly and to the right.

The key 13, contrary to the usual practice when cam units like 17 are employed, does not directly render the cam unit 17 operative by the power roller. Instead the key 13 is connected by a link 24 to a bell crank 25 pivoted at 26 and connected by a link 27 to a release lever 28, pivoted on a cross rod 29. Pivoted on a rod 30 is an arm 31 which is connected by a toggle spring 32 to one arm 33a of a coupling member 33 which is pivoted at 34 to the type bar 10. There is a train of connections, such as the one just described, for each key 13 in the keyboard.

The normal effect of the toggle spring 32 is to tend to rock both the arm 31 and member 33 in a counterclockwise direction and, by pressing diagonally upwardly to the left of the pivot 11 for the type bar to both hold the type bar against the usual rest 34 and hold the right hand end of the member 33 against a channel-shaped rebound stop bar 35. Counterclockwise movement of the arm 31 is prevented by virtue of a pin 31a carried by the arm engaging a notch in a pawl 31b carried by one arm of the release lever 28, a spring 31c anchored to the tail of the pawl 31b and a curved extension of the lever 28 holding the pawl 31b in the position shown in the drawing. The coupling member 33 is provided with a hook-shaped portion 33b capable of engaging the bail 23 under certain conditions.

Extending parallel with the bail 23 is a trip bail 36 having the side arms 36a pivoted at 37. One of the side arms 36a is extended downwardly and is bent at 36b at an angle into the plane of a release arm 38 having a slotted connection at its lower end to the upper arm of the usual release lever 11a of cam unit 17, the arm 38 being pivoted at 39a to a bracket 39 secured to the main framework 40.

When a key 13 is depressed, the bell crank 25 and release lever 28 are rocked in a clockwise di-

rection. This, through the engagement of the notched part of the pawl 31b with the pin 31a, rocks the arm 31 clockwise and has the effect of changing the point of application of the spring 32 from a line passing between the pivot point 10b and the pivot 11 for the type bar to a line passing to the left and below the pivot 10b. This causes the member 33 to rock clockwise and positions the hook-shaped portion 33b in front of the bail 23. At the same time this happens, the trip bail 36 will be rocked clockwise by the engagement of the hook-shaped portion 33b therewith under the stimulus of the spring 32. Motion thereby is transmitted to the arm 38 and by rotating said arm clockwise effects the release of the cam unit 17 in the well known way. Thereafter the operation of the cam unit 17 draws down the link 20a and operates the bail 23 in the manner described above, causing said bail 23 to travel upwardly and to the right in the drawing. The member 33 is carried along with the bail 23 and thereby propels the type bar 10 to the printing point.

The release of the key 13 permits the release lever 28 to be restored to the position shown in the drawing. The movement of the member 33 upwardly and to the right gradually shifts the direction of application of the toggle spring 32 so as to tend to restore the arm 31 to the position shown in the drawing and also to tend to disengage the member 33 from the bail 23. However, the toggle spring 32 is relatively weak in comparison to the frictional force which holds the bail 23 in engagement with the lug 33b whereby, while the type bar is being propelled toward the printing position, there will be sufficient reaction force and sufficient friction between the lug 33b and the bail 23 to maintain the member 33 in engagement with the bail. When the type bar 10 is about to strike and the bail 23 reaches the end of its stroke, member 33 will be released from the bail 23 in consequence of the relieving of the pressure between the bail 23 and lug 33b by continued movement of the type bar due to inertia, permitting the spring 32 to rock the member 33 out of engagement with the bail 23 and forcing it against the longer flange of stop bar 35. Thus, during the return stroke of the type bar the spring 32 will hold the member 33 in sliding contact with the stop bar 35 until the end of the member 33 snaps back into the position shown in the drawing.

The stop bar 35 is formed as a channel shaped member with one of the flanges longer than the other to provide an abutment for the end of the member 33. This prevents rebound of the type bar since it will be observed that any tendency of the type bar 10 to rebound will result in jamming the end of the member 33 against the longer flange of the stop bar 35.

One of the advantages of the mechanism just described over prior constructions in which the type bars are hooked to an operating bail or common actuator is that the member 33 does not render the cam unit 17 effective to operate the bail 23 until the hook-shaped portion 33b has been positioned firmly in the path of the bail 23. There is no risk that the bail 23 may hit the hook-shaped portion 33b in such a manner as to cause the member 33 to glance off as is commonly the case of mechanisms of the snatch roll type in which the hooked member is engaged with a flute or operating bail which is continuously rotated or vibrated. Thus, the type bars and other instrumentalities of the machine are

always operated positively, with the right force, and there is no possibility of incompletely operating the type bar or failing to operate it entirely.

While there have been shown and described 5 and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

15 What is claimed is:

1. A power mechanism for operating the instrumentalities of typewriting and other office machines comprising a main driving element, a driven element having an operating connection 20 to a instrumentality to be operated and shaped to have operating engagement with the first element; and means for engaging the driven element with the driving element including a toggle sprig connected at one end to said driven element 25 and an arm connected to the other end of said spring and effective in one position to bias the toggle spring in a direction to hold the driven element clear of the driving element and movable to another position in which the toggle spring is biased to engage the driven element 30 with the driving element.

2. Power operating mechanism for type bars comprising a vibratory driving element, a hook-shaped driven element having an operating connection 35 to a type bar and capable of being hooked over the driving element, an operating arm for said driven element, and spring means connecting said arm with said driven element and normally-arranged to hold the driven element unhooked from the driving element, said spring means being operative, when the arm is displaced from normal position, to hook the driven element over the driving element.

3. A power mechanism for operating the instrumentalities of typewriting and other office machines comprising a main driving element, a driven element having an operating connection to an instrumentality to be operated and shaped to have driving engagement with the first element, and means for engaging the driven element with the driving element including a spring connected at one end to said driven element and a member 50 connected to the other end of said spring and effective in one position to bias the spring in a direction to hold the driven element clear of the driving element and movable to another position in which the spring is biased to engage the driven element with the driving element.

4. A power mechanism for operating the instrumentalities of typewriting and other office machines comprising a main driving element, a driven element having an operating connection to an instrumentality to be operated and shaped to have driving engagement with the first element when coupled with the first element, and means for engaging the driven element with the driving element including a spring connected at one end to said driven element and a member 65 connected to the other end of said spring and effective in one position to bias the spring in a direction to hold the driven element clear of the driving element and movable to another position in which the spring is biased to engage the driven element with the driving element, said spring

being biased by movement of the driven element during the operation of said instrumentality to automatically disengage said driven element from the driving element.

5. A power mechanism for operating the instrumentalities of typewriting and other office machines comprising a frame having a rebound abutment, a main driving element, a driven element having an operating connection to an instrumentality to be operated and shaped to have driving engagement with the first element when coupled with the first element; and means for engaging the driven element with the driving element including a spring connected at one end to said driven element and a member connected to the other end of said spring and effective in one position to bias the spring in a direction to hold the driven element clear of the driving element and in engagement with said abutment, said member being movable to another position in which the spring is biased to engage the driven element with the driving element, said spring being biased during the operation of said instrumentality to automatically disengage said driven element from the driving element, and being operative to re-engage said driven element with the rebound abutment during the restoration of said instrumentality.

6. A power mechanism for typewriters and other office machines comprising a main power actuator, a frame having a rebound abutment, a driven element; and means to engage said driven element with said power actuator including an operating member and a spring interconnecting said element and said member and normally operative to hold said element in engagement with said abutment, said spring, when the operating member is actuated, biasing said element into engagement with said power actuator and, during the course of the operation of said element by said actuator, automatically disengaging said element from said actuator.
